UNITED STATES PATENT OFFICE

JACK F. STEPHAN, OF LOS ANGELES, CALIFORNIA

JARRING TOOL

Application filed August 9, 1929. Serial No. 384,736.

This invention relates to a jarring tool by means of which a bit or the like can be loosened when it becomes stuck in the hole.

An object of my invention is to provide a 5 jarring tool which may be coupled in the drilling string adjacent to the bit or the like, and which may be used during all of the drilling operations.

A further object is to provide a jarring 10 tool which can be used to loosen the bit or the like and which can then be used to continue the drilling without the removal of the drill pipe from the hole.

Other objects, advantages and features of 15 invention may appear from the accompanying drawing, the subjoined detailed description and the appended claims.

In the drawing

Figure 1 is a longitudinal sectional view 20 of my jarring tool.

Figure 2 is a sectional view taken on line 2-2 of Figure 1.

Figure 3 is a transverse, sectional view of 25 the slips.

Referring more particularly to the drawing, the numeral 1 indicates a threaded pin upon which the bit or the like (not shown) is screwed. A cylindrical body 2 screws on to the top of the pin 1 and a cap 3 screws on 30 to, or is otherwise suitably coupled to the top of the body 2. A sliding mandrel 4 extends through the body 2 and cap 3 and thence downwardly into the pin 1. This body is adapted to be moved longitudinally 35 of the tool when it is desired to jar or loosen the bit as will be further described.

A water course 5 extends longitudinally 40 through the mandrel 4 and a wash pipe 6 screws into the bottom of the mandrel and extends downwardly through the pin 1 and thence into the tool for the purpose of conducting the circulating fluid to the tool. A packing gland 7 is provided in the pin 1 around the wash pipe 6 to prevent the fluid 45 from passing upwardly around the outside

of the wash pipe. In the body 2 I provide a pair of slips 8-8 which are set in diametrically opposed recesses 9-9, and the outer surfaces of the slips are tapered and bear against an upwardly tapered surface in the recess 9 so that the slips are tightly held 50 against the mandrel 4. The surfaces 10-10 on the mandrel 4 against which the slips 8 bear, are very slightly tapered so that a considerable strain is required to move the mandrel upwardly past the slips 8. A spring 11 is provided under each of the slips 8, which spring urges the slips upwardly in their respective recesses against a shoulder 12. An adjusting screw 13 extends through the body 2 and bears against a shim 13' on the slips 8 for the purpose of adjusting the slips inwardly against the surface 10 of the mandrel. 55

The cap 3 is formed with a pair of elongated slots or grooves 14-14, and the mandrel 4 is formed with a pair of integral lugs 15-15 which fit into the grooves 14 and are 60 slidably therein. Thus it will be seen that the mandrel 4 may be moved longitudinally of the tool, but when the mandrel is rotated, 70 the entire tool including the body 2 and pin 1 are also rotated and will therefore drive the bit or other tool. A suitable coupling pin 16 is formed on the top of the mandrel 4 so that the drill pipe or the like can be coupled 75 thereto.

In operation the drilling continues in the usual manner and after the bit becomes stuck, it may be jarred loose in the following manner. The drill pipe is pulled upwardly, 80 which in turn pulls the mandrel 4 upwardly and causes the surface 10 to move past the slips 8. This movement, of course, requires considerable force and as soon as the surface 10 has moved past the slips 8 the mandrel 4 85 will be suddenly released and the lug 15 will strike against the top of the cap 3 thus imparting a jar to the bit. The mandrel 4 is now lowered and the small shoulders 17 at the bottom of the surface 10 will engage the 90

slips 8 and push them downwardly against the tension of the springs 11. When this action occurs, the slips 8 are moved outwardly, due to the construction of the recesses 9 and the mandrel 4 is returned to the position shown in Figure 1.

The springs 11 immediately carry the slips 8 upwardly as soon as the shoulder 17 has passed. The action above stated is repeated 10 as many times as required in order to remove the bit.

Having described my invention, I claim:

1. A jarring tool comprising a body, a mandrel extending into the body, coupling 15 means on the body to which a bit is adapted to be secured, coupling means on the mandrel to which drill pipe is adapted to be secured, means slidably mounting said mandrel in the body, said slidably mounting means being

20 adapted and arranged to rotate the body when the mandrel is rotated and slips in said body engaging the mandrel, said slips retarding the upward movement of the mandrel.

25 2. A jarring tool comprising a body, a mandrel extending into the body, a cap on the body, said cap having longitudinally extending grooves therein, lugs on the mandrel extending into the grooves, said lugs being 30 adapted to rotate the body when the mandrel is rotated, and a pair of slips engaging the mandrel whereby the upward movement of the mandrel is retarded.

3. A jarring tool comprising a body, a 35 mandrel extending into the body, a cap on the body, said cap having longitudinally extending grooves therein, lugs on the mandrel extending into the grooves; said lugs being adapted to rotate the body when the mandrel 40 is rotated, and a pair of slips engaging the mandrel whereby the upward movement of the mandrel is retarded, a tapered surface upon the mandrel against which the slips are adapted to rest, and springs under the slips 45 urging them upwardly.

4. A jarring tool comprising a body, a mandrel extending into the body, a cap on the body, said cap having longitudinally extending grooves therein, lugs on the mandrel 50 extending into the grooves, said lugs being adapted to rotate the body when the mandrel is rotated, and a pair of slips engaging the mandrel whereby the upward movement of the mandrel is retarded, adjusting screws extending through the body against the slips 55 and a spring under each of the slips urging the same upwardly.

5. A jarring tool comprising a body, a pin 60 screwed into the bottom of the body, a cap screwed on to the top of the body, a mandrel extending through the cap, and body, said cap having grooves formed therein, lugs on the mandrel extending into the grooves, said lugs being adapted and arranged to rotate the body when the mandrel is rotated, a wash 65

pipe depending from the mandrel and extending through the pin, a pair of slips in the body bearing against the mandrel, a tapered surface on the mandrel against which the slips bear, a spring over each of the slips urging the same upwardly and an adjusting screw extending through the body against each of the slips.

In testimony whereof, I affix my signature.

JACK F. STEPHAN.
